WELL BAILER

Eugene Graham, Jr., Los Angeles, Calif., assignor
to Grant Oil Tool Company, Los Angeles, Calif.,
a corporation of California

Application January 8, 1945, Serial No. 571,759

8 Claims. (Cl. 166—19)

1

This invention has to do with improvements in hydrostatic well bailers of the general type comprising a charge-receiving chamber normally sealed against the entry of well fluid by a suitable closure, typically a frangible member or disc, and means responsive to predetermined movement of the bailed in the well for opening the closure to permit flow of a sand and well fluid charge into the chamber. More particularly, the invention deals with bailers in which the closure is opened by a mandrel part, as where a frangible disc-type closure is to be broken by projecting a breaker mandrel against the disc.

One of my primary objects is to provide an improved control and actuating means for the closure opening or breaking mandrel. In accordance with the invention, the mandrel is spring-actuated in its closure opening travel and normally is maintained in retracted condition by a latch device adapted to be released to permit projection of the mandrel by its spring.

A further feature and object is the provision of a control device operable as an incident of bottoming the bailed in the well, to release the mandrel latch. Preferably, though typically, I employ a secondary or tripping mandrel operable upon upward displacement within the bailed to release the latch device and then, upon opening of the closure, to permit the charge to be taken upwardly through the bores of both mandrels, into the charge-receiving chamber.

These objects are accomplished by a bailed structure having various other novel features and details, all of which will be fully understood from the following detailed description of the invention as embodied in a typical and illustrative form. Throughout the description reference is had to the accompanying drawing, in which:

Fig. 1 is a sectional view of the bailed showing the disc breaker mandrel in its retracted or latched position;

Fig. 2 is a similar view showing the position of the mandrel after its projection against the disc;

Fig. 3 is a fragmentary side elevation showing the unloading sleeve turned to open the dump port; and

Fig. 4 is a cross-section on line 4—4 of Fig. 2.

The bailed structure comprises a body including a tubular sub 10 having a threaded connection at 11 with a pipe 12 of whatever length required to provide a charge receiving chamber 13 of the desired capacity. As will be understood without necessity for specific illustration and further description, the pipe 12 may be provided at its upper end with any of the usual types of

pressure release valves and a connection, usually by way of a jar, with a wire line on which the bailed is run into and out of the well. The sub 10 is threadedly coupled by the unloading sleeve 14 with the tubular sub 15, and the latter has a threaded connection at 16 with the lower section 17 of the body assembly.

The sub 10 has an unloading opening or dump port 18 adapted to be brought into registry with 10 a corresponding opening 19 in the sleeve 14 by turning the sleeve from the position of Fig. 1 to that illustrated in Fig. 2. Normally the sleeve is held against accidental turning by lock nut 20 threaded on the sub 15. As shown in Fig. 4, the 15 sub 15 has flattened surfaces 21 for engagement by a wrench to facilitate opening and closing of the unloading ports. With the parts in the position of Fig. 2, the charge receiving chamber 13 may be closed at its lower end by insertion 20 through the openings 18 and 19 of a concave frangible disc 22 which fits within an annular recess 23 within the sub 10.

The body contains a vertically movable disc breaker mandrel 24 comprising a tubular stem 25 having a bore 26 forming a passage through which the sand and well fluid charge is taken, upon breaking of the disc 22, upwardly into the chamber 13. The mandrel carries a check valve 27 which seats upon reception of the charge to 25 retain the latter by preventing its return flow down through the mandrel.

The mandrel has a disc breaker head 28 comprising a plurality of points 29 adapted to be impacted against and to rupture the disc 22, the 35 points also serving to form a cage for the ball check 27. When released from the position of Fig. 1, the mandrel is projected against the disc by a coil spring 30 confined between the head 28 and the internal body shoulder 31.

As originally set and while lowered into the well, the mandrel is releasably held in the retracted position of Fig. 1 by a suitable latch device 32 which preferably, though typically, comprises a ring 33 clamped between the end 34 of 40 sub 15 and shoulder 35 inside the lower body section 17. Ring 33 carries a plurality of integral, circularly arranged resilient latch fingers 36 engageable against annular mandrel shoulder 37 at the bottom of the tapered surface 38. Below 45 shoulder 37 the latch fingers may project outwardly at 39, substantially as illustrated. The end of the mandrel stem 25 may be interiorly threaded at 40 for reception of a seating tool to be used for pulling down and engaging the mandrel with the latch assembly 32.

The latch fingers 36 are releasable from holding engagement with the mandrel 24 by relative upward movement of a tripping mandrel, generally indicated at 41, comprising a tube 42 slidably vertically on the lower end of the disc breaker mandrel stem 25 within bore 44. Normally the tripping mandrel is supported by the engagement of its head 45 on the body shoulder 46. The tripping mandrel may carry the usual mixer shoe 47 held in adjusted position by lock nut 48.

As previously indicated, the bailers are lowered into the well with the parts positioned as illustrated in Fig. 1. As further lowering of the tripping mandrel is arrested by its reaching the bottom of the well (or in some operations by the equivalent engagement with a plug or barrier at some intermediate location in the well) continued downward movement of the latch fingers 36 brings their divergent ends 39 against the upper end of the tripping mandrel, whereupon the fingers are spread to release the disc breaker mandrel. The latter thereupon is projected by spring 30 upwardly against the disc 22, and the resultant breaking of the disc produces an inflow of sand and well fluid through the mixing shoe 47 and upwardly through the mandrel passages into the charge receiving chamber 13. The bailed then is removed from the well and in the condition substantially as illustrated in Fig. 2, except for possible greater compression of the spring 30 due to the weight of the charge.

I claim:

1. A well bailed comprising a body containing a charge-receiving chamber, a closure at the bottom of said chamber and initially preventing upward flow of well fluid into said chamber, an upper tubular mandrel section carried by the bailed body and movable upwardly within the body to open said closure, a spring interposed between said mandrel section and the body for projecting said mandrel upwardly in its closure opening movement, means carried by the body and initially holding said mandrel against such upward movement, and a lower tubular tripping mandrel slidably carried by and depending below the body and displaceable upwardly relative to the body upon engagement with the bottom of the well to engage and release said holding means from said upper mandrel section to permit it to open said closure and permit the well fluid to flow upwardly through both mandrels into said chamber.

2. A well bailed comprising a body containing a charge-receiving chamber, a closure at the bottom of said chamber and initially preventing upward flow of well fluid into said chamber, an upper tubular mandrel section carried by the bailed body and movable upwardly within the body to open said closure, a spring interposed between said mandrel section and the body for projecting said mandrel upwardly in its closure opening movement, means carried by the body and initially holding said mandrel against such upward movement, and a lower tubular tripping mandrel slidably carried by and depending below the body and telescopically receiving the lower end of the upper mandrel, said tripping mandrel being displaceable upwardly relative to the body upon engagement with the bottom of the well to engage and release said holding means from said upper mandrel section to permit it to open said closure and permit the well fluid to flow upwardly through both mandrels into said chamber.

3. A well bailed comprising a body containing

a charge-receiving chamber, a closure at the bottom of said chamber and initially preventing upward flow of well fluid into said chamber, an upper tubular mandrel section carried by the bailed body and movable upwardly within the body to open said closure, a spring interposed between said mandrel section and the body for projecting said mandrel upwardly in its closure opening movement, a resilient latch element initially holding said mandrel against such upward movement, and a lower tubular tripping mandrel slidably carried by and depending below the body and displaceable upwardly relative to the body upon engagement with the bottom of the well to flex and release said latch element from said upper mandrel section to permit it to open said closure and permit the well fluid to flow upwardly through both mandrels into said chamber.

4. A well bailed comprising a body containing a charge-receiving chamber, a closure at the bottom of said chamber and initially preventing upward flow of well fluid into said chamber, a tubular mandrel carried by the bailed body and movable upwardly within the body to open said closure, a spring interposed between said mandrel section and the body for projecting said mandrel upwardly in its closure opening movement, a plurality of resilient latch fingers carried by the body and stationarily held each at one end thereof and initially engaging and holding the mandrel against such upward movement, and a tubular tripping mandrel slidably carried by and extending below the body and displaceable relatively upwardly therein when bottomed in the well to engage and flex said latch fingers from said holding engagement with the first mentioned mandrel to permit it to open said closure and thereby permit fluid flow up through both mandrels into said chamber.

5. A well bailed comprising a body containing a charge-receiving chamber, a closure at the bottom of said chamber and initially preventing upward flow of well fluid into said chamber, a tubular mandrel carried by the bailed body and movable upwardly within the body to open said closure, a spring interposed between said mandrel section and the body for projecting said member upwardly in its closure opening movement, a stationary ring surrounding said mandrel within the body and carrying a plurality of integral depending spring latch fingers initially engaging a shoulder on the mandrel and holding the mandrel against such upward movement, and a tubular tripping mandrel slidably carried by and extending below the body and displaceable relatively upwardly therein when bottomed in the well to flex and release said latch fingers from said holding engagement with the first mentioned mandrel to permit it to open said closure and thereby permit fluid flow up through both mandrels into said chamber.

6. A well bailed comprising a body containing a charge-receiving chamber, a closure at the bottom of said chamber and initially preventing upward flow of well fluid into said chamber, a tubular mandrel carried by the bailed body and movable upwardly within the body to open said closure, a spring interposed between said mandrel section and the body for projecting said member upwardly in its closure opening movement, a ring surrounding said mandrel within the body and carrying a plurality of integral depending spring latch fingers initially engaging a shoulder on the mandrel and holding the mandrel against such upward movement, and a tubular tripping man-

drel telescopically receiving the lower end of the first mentioned mandrel inside the body, said tripping mandrel slidably carried by and extending below the body and being displaceable upwardly relative to the body when bottomed in the well to flex and release said latch fingers from said holding engagement with the first mentioned mandrel to permit it to open said closure and thereby permit fluid flow up through both mandrels into said chamber.

7. A well bailer comprising a body including an upper section containing a charge-receiving chamber, a bottom section, and a tubular sub interconnecting said sections, a closure at the bottom of said chamber and initially preventing the flow of well fluid into said chamber, an upper tubular mandrel carried by the bailer body and movable upwardly within said sub to open said closure, a coil spring contained within the sub and operable to project said mandrel upwardly in its closure opening movement, means initially holding said mandrel against such upward movement, and a lower tubular tripping mandrel slidably carried by and depending below the body and displaceable upwardly relative to the body upon engagement with the bottom of the well to engage and release said holding means from said upper mandrel section to permit it to open said closure and permit the well fluid to flow upwardly through both mandrels into said chamber.

8. A well bailer comprising a body including an

upper section containing a charge-receiving chamber, a bottom section, and a tubular sub interconnecting said sections, a closure at the bottom of said chamber and initially preventing the flow of well fluid into said chamber, an upper tubular mandrel carried by the bailer body and movable upwardly within said sub to open said closure, a coil spring contained within the sub and operable to project said mandrel upwardly in its closure opening movement, means engaged against the lower end of said sub and comprising a latch element initially holding said mandrel against such upward movement, and a lower tubular tripping mandrel slidably carried by and depending below the body and displaceable upwardly relative to the body upon engagement with the bottom of the well to engage and release said holding means from said upper mandrel section to permit it to open said closure and permit the well fluid to flow upwardly through both mandrels into said chamber.
